HYDRAULIC LIFT JACK

Herbert E. Page, Pasadena, Calif.

Application July 5, 1943, Serial No. 493,567

7 Claims. (Cl. 60—52)

This invention relates to hydraulic pressure-actuated devices and, in its more particular aspects, it relates to jacks. The invention has for one of its objects the provision of a jack in which the work-lifting member is rapidly moved into contact with the work with minimum operation and without the application of fluid pressure.

Another object is to provide a jack of this character in which the fulcrum for the operating lever is raised to follow the movement of the work-lifting member.

Another object is the provision of a jack employing a telescopic piston and permitting use of a relatively short cylinder.

A further object of my invention is the provision of a double-acting pressure-generating means.

A still further object is the provision of a highly simplified, durable jack which may be manufactured with relative economy.

Additional advantages are inherent in my invention and how those, as well as the objects hereinabove particularly enumerated, are achieved will become apparent from the following detailed explanation of presently preferred adaptations illustrated in the accompanying drawings. I wish it understood, however, that in its broader aspects as defined by the accompanying claims, my invention is not to be confined to the details of structure and association of parts illustrated in the drawings, since, with the understanding of the invention to be derived from the accompanying specification and drawings, various modifications and adaptations will occur to those skilled in the art.

In the accompanying drawings:

Fig. 1 is a vertical sectional view of one form of my invention taken on line 1—1 of Fig. 2, some parts being shown in elevation;

Fig. 2 is a top plan view of Fig. 1;

Fig. 3 is a medial vertical sectional view showing a variational form of my invention;

Fig. 4 is a fragmentary vertical section showing a further variational form of the invention;

Fig. 5 is a perspective showing a further variational form of my invention;

Fig. 6 is a medial longitudinal section of Fig. 5; and

Fig. 7 is a front elevation of Fig. 5.

Referring now to Figs. 1 and 2, I show a body 5 in the interior of which I provide a relatively large cylinder 6 and a parallel, relatively small, cylinder 7, around which there is a hydraulic fluid reservoir 8 vented to atmosphere through port 9a in a threaded plug 9.

A work-lifting piston 10 is reciprocally mounted in cylinder 6 and a pumping piston 12 is reciprocally mounted in cylinder 7. An operating lever 15 has one of its ends bifurcated and pivotally connected by pin 16 to the piston 10 and is fulcrumed on the flattened top end 12a of piston 12 by means of pin 17 and link 18.

Beneath the cylinders I provide in the body a valve-receiving bore 20 within which I secure, as by snap ring 21, a valve member generally designated 25. This valve member includes a body 26 having annular grooves to receive sealing rings 27. A poppet valve 30, having stems 31, 32, is reciprocally mounted in the bore of a plug 33 threaded into one end of the valve body, an annular sealing ring 34 being provided between the plug and body bore. Stem 31 is of squared cross-section to permit passage of fluid therearound. A second poppet valve 37, having a stem 38 and a bore 39, is reciprocally mounted in the valve body bore. A coil spring 40 seats at one end in the bore of a plug 42 threaded into the valve body bore and seats at its other end against poppet 37 to urge the latter against its seat. A spring 45 urges poppet 30 against its seat. Plug 42 carries a sealing ring 46. Valve member 25 has a reduced diameter portion providing an annular chamber 47 and a reduced diameter portion providing an annular chamber 48. A pull member 49 is provided on the outer end of the valve member 25.

Cylinder 7 communicates with the reservoir 8 through passageways 50, 51, 52, said communication being controlled by poppet 30, cylinder 7 35 communicates with the cylinder 6 through passageway 50, 52, 55, 54 and 53, and cylinder 6 communicates with the reservoir 8 through passageways 53, 57, the latter of which is controlled by a spring-pressed ball check valve 60 mounted in 40 a chamber to which access is provided by a threaded plug 60a. A cam 70 is mounted on a shaft 71 journaled in the body, the shaft having secured thereto exterior of the body an operating member 72 (Fig. 2).

To operate the device from the starting position shown in Fig. 1, the lever 15 is first lifted to move piston 12 outwardly of the cylinder, which causes a sufficient vacuum in cylinder 7 to unseat poppet 30 and draw hydraulic fluid 50 into cylinder 7 through passageways 51, 52 and 50. Then, upon downward pressure on the lever, it is fulcrumed about the pivot pin 17 and its left-hand end lifts piston 10 into engagement with the work to be engaged (not shown), there 55 being insufficient resistance to movement of pis-

ton 10 prior to contact with the work to cause poppet 37 to be unseated against the pressure of spring 40 by such downward pressure on piston 12. This upward movement of piston 10 in its cylinder draws fluid into cylinder 6 from the reservoir through passageways 53, 57. After piston 10 has thus contacted the work to be lifted, valve 60 ceases to function, but as the lever 15 is operated to impart the pumping strokes to piston 12, the resistance to upward movement of piston 10 caused by contact with the work is sufficient to cause spring 40 to yield upon the pumping strokes of piston 12, permitting fluid to pass from cylinder 7 to cylinder 6. It will be observed that in operation of the lever, the fulcrum point alternately shifts from one piston to the other until piston 10 contacts the work, and is raised in consonance with elevation of the piston 10.

When it is desired to lower the work, member 72 is rotated to rotate shaft 11 and cam 10, the latter contacting the stem 31 to first unseat poppet 30 and release pressure in cylinder 1. Further inward movement of the stem 31 causes stem 32 to contact stem 38 and unseat poppet 37 to release the pressure in cylinder 6.

In practice, spring 40 is proportioned in strength to the resistance normally to be offered to movement of the piston 10 when that piston is not burdened by any load to be lifted. Thus poppet 37 will remain seated until spring 40 yields under the pressure of the pumping stroke of piston 12 after piston 10 contacts the load. Spring 45 is preferably made relatively weaker than spring 40 to permit it to yield upon the suction stroke of piston 12.

In the variational form of my invention shown in Fig. 3, I show a body 80 having a relatively large medial cylinder 81 and a pair of relatively smaller cylinders 82, 82a disposed one on each side of the larger cylinder. A hydraulic fluid reservoir 85 surrounds the cylinders and is in communication therewith through ports 86, 87, 88 controlled respectively by check valves 89, 90, 91, which valves seat towards the reservoir.

A work-lifting piston 95 having a work-engaging top end portion 95a is reciprocally mounted in cylinder 81, and pumping pistons 96, 96a are reciprocally mounted respectively in cylinders 82, 82a.

An operating handle 97 has a medial portion encompassing and pivotally connected to piston 95 by means of pin 97a and is pivotally connected at each side thereof to the respective pumping pistons 96, 96a by means of pins 97b, links 98 and pins 98a.

Communication between cylinder 81 and the respective cylinders 82, 82a is established by ports 99, 100, respectively, said ports being controlled by coaxial poppet valves 101, 102, respectively, whose inner ends are spaced apart, the valves being urged into seating position towards the respective cylinders 82, 82a by coil spring 103. The reservoir 85 is vented to atmosphere by means of ports 105 provided in threaded plugs 106. For actuating valves 89, 90, 91 in the manner to be hereinafter described, I provide a shaft 108 journaled adjacent one end in one side of the body and journaled adjacent its other end in a bearing plug 109 threadedly mounted in the body. Three longitudinally spaced eccentric cams 110, 111, 112 are secured on the shaft in such relative position that cam 110 will lift poppet 89 after cams 111, 112 lift poppets 90, 91 upon rotation of the shaft.

Up and down movement of the respective ends of the lever, pivoting about pin 97a, causes fluid to be alternately drawn into the cylinders 82, 82a past the respective valves 90, 91 and progressively lifts the piston 95 until it contacts the work to be lifted, drawing fluid into cylinder 81 past valve 89. After the load has thus been contacted by the piston 95, each subsequent downward stroke of the respective pistons 96, 96a forces fluid past the respective valves 101, 102 into cylinder 81 to raise piston 95 hydraulically. Spring 103 is strong enough to prevent either of the valves 101, 102 from unseating prior to the time piston 95 contacts the work to be lifted. Of course, as piston 95 is thus progressively raised, the fulcrum points for lever 97 are commensurately raised.

When it is desired to lower the load, handle 115 is operated to rotate shaft 108 and first bring the cams 111, 112 into lifting engagement with poppets 90, 91 and then to bring cam 110 into lifting engagement with poppet 89, to release the pressure in the various cylinders.

In Fig. 4 I show a further variational form of device incorporating the feature of telescopic pistons. Here the valve and port structures are as before described, the body being divided into upper section 125 and lower section 125a. A pair of cylinders 126, 127 and a fluid reservoir 128 are provided in the body, the reservoir being vented to atmosphere through port 129.

Telescopic pistons generally designated by the numerals 130, 131 are mounted in cylinders 126 and 127, respectively. Piston 130 comprises an outer portion 130a and an inner portion 130b reciprocally mounted in said outer portion. Piston portion 130a has an enlarged diameter inner end providing an upwardly facing stop shoulder 135 engageable against shoulder 136 provided by threaded plug 125b; and inner piston portion 130b has an enlarged diameter inner end providing an upwardly facing stop shoulder 140 which is engageable against shoulder 141 provided adjacent the top end of the bore of piston portion 130a, both said stops being to limit upward movement of the piston portions. Transversely through the side wall of piston portion 130a adjacent the top end I provide holes 143 slidably carrying detent pins 144 whose rounded inner ends are normally urged into the annular recess 147 in piston portion 130b by means of a spring 145 fitting in grooves in outer ends of the pins. The top end of piston 130b carries a sleeve 130c which presents a downwardly facing annular shoulder 146 seating against top end of piston 130a when the device is fully telescoped.

Piston 131 is likewise composed of outer portion 131a and inner portion 131b. The inner end of piston portion 131a is of increased diameter to provide an upwardly facing stop shoulder 150 engageable against the shoulder 151 provided by the plug ring 152, and inner piston portion 131b has an enlarged diameter inner end providing an upwardly facing stop shoulder 154 engageable against the shoulder 155. The top end of piston portion 131b is flattened and carries a transverse pin 156 to engage against the top end of piston portion 131a when the device is telescoped.

Transverse holes 160 are provided through plug 152 to slidably receive detent pins 161 whose inner ends engage in an annular recess 162 provided in the lower portion of piston 131a when that piston is at the outermost limit of its travel,

said pins being yieldingly urged inwardly by spring 164.

The top end of piston portion 131a carries a sleeve 166 whose bottom edge is engageable against the top edge of plug 152 as a stop when the device is telescoped. Transversely through sleeve 166 and piston portion 131a holes 170 are provided to slidably receive detent pins 171 whose inner ends are engageable in annular recess 172 in piston portion 131b. Pins 171 are yieldingly urged towards the recess by spring 174.

An operating lever 176 has a bifurcated inner end pivotally mounted on the upper end of piston portion 130b and is fulcrumed atop a link 177 carried by the upper end of piston portion 131b. Pins 178 secure the lever to the link and the link to the piston.

This device is operated in the manner of Figs. 1 and 2 except that after piston 130a reaches the upper limit of its movement, further pumping operation of piston 131 forces the inner piston portion 130b upwardly with each pumping stroke, first overcoming the pressure of spring 145 to permit disengagement of pins 144 from recess 147; and after piston portion 131a reaches the upper limit of its movement, pins 161 engage in recess 162 and pins 171 disengage from recess 172, permitting inner piston portion 131b to be reciprocated and gradually moved upwardly with each stroke, so that the fulcrum point for lever 176 rises in consonance with upward movement of the pistons.

In Figs. 5-7 I show a further variational form which my invention may take. Here the body 180 has substantially the same interior construction as before described in connection with Figs. 1 and 2 and corresponding parts are given like reference numerals. The body, however, is of a rounded cross-section and the means for unseating the valve elements in valve housing 26 is a threaded plug member 181 which may be screwed inwardly to engage the end of valve stem 31. Also, the body is mounted in a flanged base 182, and to provide access to the valve housing 26 the body has a detachable plate 180a and the base flange has a detachable plate 182a.

Here the operating lever 183 has two arms 183a, 183b whose inner ends are bifurcated to receive the respective downwardly disposed arms 184a of a yoke 184, being pivotally connected to the arms by pins 185. Yoke 184 is secured to the upper end of piston 10 by cross pin 186. Piston 12 is operatively secured to the arms 183a, 183b by links 187a, pivotally secured at one end to a yoke 187 and pivotally secured at their other ends to arms 183a, 183b, respectively. Yoke 187 is secured to the projecting end of piston 12 by cross pin 190.

The operation of the device of Figs. 5-7 is like that of Figs. 1 and 2 except that the operating lever is operated from a lower plane so as to be further removed from the work being lifted.

I claim:

1. In a hydraulic jack, the combination of a body presenting a pair of cylinders and a fluid reservoir, a pumping piston reciprocally mounted in the first cylinder and projecting therefrom, a work piston reciprocally mounted in the second cylinder and projecting therefrom, said body presenting a first fluid passageway communicating with the reservoir and the first cylinder and a second fluid passageway establishing communication between the first and second cylinders, a check valve in the first fluid passageway seating towards the reservoir, said valve being mov-

- able off its seat by vacuum created by the suction stroke of the pumping piston whereby fluid is drawn from the reservoir into the first cylinder, a check valve in the second passageway seating towards the first cylinder, a spring urging the last-named valve into seating position, said spring being yieldable to fluid pressure created by the pumping stroke of the pumping piston only when the work piston is burdened with a work load, an operating lever pivotally connected at spaced points therealong to the projecting ends of the respective pistons, said lever, when fulcrumed on its said pivotal connection to the pumping piston, functioning to move the work piston towards engagement with the work independently of any fluid pressure in the second cylinder, a third fluid passageway in the body establishing communication between the reservoir and the second cylinder through which fluid is drawn into the second cylinder during said last-named movement of the work piston, and a check valve controlling the third passageway, said last-named valve seating towards the reservoir.
2. In a hydraulic jack, the combination of a body presenting a pair of cylinders and a fluid reservoir, a pumping piston reciprocally mounted in the first cylinder and projecting therefrom, a work piston reciprocally mounted in the second cylinder and projecting therefrom, said body presenting a first fluid passageway communicating with the reservoir and the first cylinder and a second fluid passageway establishing communication between the first and second cylinders, a self-closing check valve in the first fluid passageway seating towards the reservoir, said valve being movable off its seat by vacuum created by the suction stroke of the pumping piston whereby fluid is drawn from the reservoir into the first cylinder, a check valve in the second passageway seating towards the first cylinder, said last-named valve being movable off its seat by fluid pressure created by the pumping stroke of the pumping piston only when the work piston is burdened with a work load, an operating lever pivotally connected at spaced points therealong to the projecting ends of the respective pistons, said lever, when fulcrumed on the pumping piston, functioning to move the work piston towards engagement with the work independently of any fluid pressure in the second cylinder, means responsive to vacuum in the second cylinder to pass fluid thereto from the reservoir when the work piston is being so moved towards engagement with the work, and means for releasing fluid pressure in the cylinders including a valve unseating member.
3. In a jack, the combination of a body presenting a work cylinder and a pair of pump cylinders one on each side of the work cylinder, a fluid reservoir, fluid passageways establishing communication between the respective pump cylinders and the reservoir, a self-closing check valve in each passageway seating towards the reservoir, ports in the body establishing communication between the work cylinder and the respective pump cylinders, check valves controlling the respective ports and seating towards the respective pump cylinders, a work-lifting piston reciprocally mounted in the work cylinder, spring means cooperating with the last-named check valves to maintain them seated when the work-lifting piston is not under load, a pumping piston reciprocally mounted in each pump cylinder, a lever pivotally connected at spaced points there-

along to each of the respective pistons and means responsive to vacuum in the work cylinder to pass fluid thereto from the reservoir, said means including a fluid passageway in the body and a self-closing check valve therein seating towards the reservoir.

4. In a hydraulic jack, the combination of a body presenting a pair of cylinders and a fluid reservoir, a pumping piston reciprocally mounted in the first cylinder and projecting therefrom, a work piston reciprocally mounted in the second cylinder and projecting therefrom, said body presenting a first fluid passageway communicating with the reservoir and the first cylinder and a second fluid passageway establishing communication between the first and second cylinders, a check valve in the first fluid passageway seating towards the reservoir, said valve being unseatable by vacuum created by the suction stroke of the pumping piston whereby fluid is drawn from the reservoir into the first cylinder, a check valve in the second passageway seating towards the first cylinder, a spring urging the last-named valve into seating position, said spring being sufficiently strong as to be yieldable to fluid pressure created by the pumping stroke of the pumping piston only when the work piston is burdened with a work load, an operating lever pivotally connected at spaced points therealong to the projecting ends of the respective pistons, said lever, when fulcrumed on the pumping piston, functioning to move the work piston towards engagement with the work independently of any fluid pressure in the second cylinder, means for releasing fluid pressure in the cylinders including a valve unseating member, a fluid passageway in the body establishing communication between the work cylinder and reservoir, a check valve controlling said passageway and seating towards the reservoir, and cam means engageable against said last-named valve in a manner to unseat the valve.

5. In a jack, the combination of a body having a fluid reservoir, a work cylinder and a pump cylinder, a pair of telescopic pistons reciprocally mounted in the respective cylinders for movement in parallel planes, a fluid passageway in the body providing communication between the reservoir and pump cylinder, a self-closing check valve in said passageway seating towards the reservoir, a second fluid passageway in the body providing communication between the cylinders, a spring-loaded check valve in the second passageway seating towards the pump cylinder, the spring load on the last-named check valve being sufficient to maintain it seated when the piston mounted in said work cylinder is not under load, an operating lever pivotally secured at spaced points therealong to the respective pistons whereby downward movement of one end of the lever

fulcrums the lever on one of the pistons and exerts a lifting force on the other piston, a third passageway in the body providing communication from the reservoir to the work cylinder, and a self-seating check valve seating towards the reservoir in the third passageway.

6. In a jack, the combination of a body presenting a fluid reservoir and a pair of cylinders, a work piston reciprocally mounted in the second cylinder and a pumping piston reciprocally mounted in the first cylinder, self-closing check valve means operable in response to vacuum in the first cylinder to pass fluid thereto from the reservoir, a fluid communication passageway between the cylinders, a check valve in the passageway seating towards the first cylinder, the spring load on the last-named valve being sufficient to maintain said valve seated when the work piston is not under load, each of said pistons comprising an outer sleeve portion, inter-engaging means in the cylinder and sleeve operable to limit outward movement of the sleeve relative to the cylinder, an inner member slidably mounted in the sleeve portion, yieldable detent means on the sleeve engageable against the inner member whereby to oppose movement of the inner member relative to the sleeve, an operating lever pivotally connected at points spaced longitudinally thereof to the inner members of the respective pistons, and means responsive to vacuum in the second cylinder to pass fluid thereto from the reservoir, said last-named means including a fluid passageway in the body and a self-closing check valve in said passageway seating towards the reservoir.

7. In a jack, the combination of a body presenting a fluid reservoir, a pumping cylinder and a work cylinder, a pumping piston reciprocally mounted in the pumping cylinder, a work piston reciprocally mounted in the work cylinder, self-closing check valve means operable in response to vacuum in the pumping cylinder to pass fluid thereto from the reservoir, a fluid communication passageway in the body providing communication between the cylinders, a check valve in the passageway seating towards the pumping cylinder, spring means for maintaining the last-named valve seated when the work piston is not under load, each piston having a portion projecting upwardly beyond the body, links pivotally connected at their top ends to the projecting portions of the respective pistons and being disposed downwardly therefrom, an operating lever pivotally connected to the lower ends of the respective links at points spaced apart longitudinally of the lever, and self-closing means responsive to vacuum in the work cylinder to pass fluid thereto from the reservoir.
